UNITED STATES PATENT OFFICE.

DOUGLAS GORDON, OF WORCESTER, MASSACHUSETTS, ASSIGNOR TO MARCUS MASON & COMPANY, OF NEW YORK, N. Y., A CORPORATION OF NEW YORK.

COFFEE-DRIER.

No. 842,456.

Specification of Letters Patent.

Patented Jan. 29, 1907.

Application filed May 1, 1906. Serial No. 314,612.

To all whom it may concern:

Be it known that I, DOUGLAS GORDON, a subject of the King of Great Britain, and a resident of Worcester, county of Worcester, 5 State of Massachusetts, have invented certain new and useful Improvements in Coffee-Driers, of which the following is a specification, reference being had to the accompanying drawings, forming a part thereof.

10 My invention relates to improvements in coffee-driers of the type employing two perforated concentric cylinders adapted to receive a charge in the annular space between them and provided with means for admitting 15 air to the interior of the inner cylinder.

My present invention resides in a novel means for admitting and distributing air within the inner cylinder; and it consists in means having a connection with a source of 20 air-supply at one end only of the inner cylinder, said means admitting a part only of the air thus received at such end of the cylinder, and means for carrying the remainder of the air thus admitted to the opposite end of the 25 cylinder, to be discharged into the said cylinder at that end thereof.

In order that my invention may be fully understood, I will describe in detail, with reference to the accompanying drawings illustrating same, an apparatus embodying my invention and will then point out the novel features in the claim.

30 In the drawings, Figure 1 is a view in central vertical longitudinal section through a 35 drier embodying my invention, and Fig. 2 is a detail view in transverse section through a portion thereof upon the plane of the line 2 2 of Fig. 1.

The drier comprises an outer perforated 40 cylinder 5, an inner perforated cylinder 6, closed end heads 7, and trunnions 9 and 10, secured to said end heads, supporting the said drier in bearings 13 upon standards 14. The charge to be dried, which may be different kinds of grains, berries, and the like, and particularly coffee-berries, is arranged to be contained in the annular space between the two cylinders 5 and 6, the space within the cylinder 6 being unoccupied, so far as the 45 berries are concerned. I make no claim,

however, to this particular form of drier *per se*, the essence of the present invention being the means, in combination therewith, for introducing air to the space within the cylinder 6, from which it may be discharged through 55 the perforations in the said cylinder 6 to the annular charging space between the two cylinders 5 and 6 and thence outward through the perforations in the cylinder 5. This is as follows:

The trunnions 9 and 10 are made hollow, as shown, one of the trunnions 9 being open clear through and arranged to be connected with a source of air-supply, (under pressure,) the other trunnion being closed by means of 60 a cap 15, the inner portion of which acts as a deflector. Arranged centrally within the cylinder 6 and extending with its ends into both of the said trunnions is a central open-ended tube 11, the outer diameter of said 65 tube being less than the inner diameter of the said trunnions. The tube is connected with the said trunnions by means of spiders 12, said spiders leaving free passage for the currents of air through the annular passage be- 70 tween the said tube and trunnions..

75 Currents of air entering the trunnion 9 will be divided, a part thereof passing on through the central tube 11 and a part entering the cylinder 6 at the end at which the 80 said trunnion 9 is arranged. That part of the currents which passes on through the tube 11 will enter the trunnion 10 and will be deflected by means of the deflector 15 to the annular space around the said tube, to be 85 discharged into the cylinder 6 at the end thereof, at which is the trunnion 10. By this means the air will be evenly distributed within the inner cylinder 6, and hence evenly distributed throughout the apparatus. The 90 currents of air will be divided and will be admitted half and half to opposite ends of the drier in a very simple manner, even though the connection to the air-supply is at one end only thereof.

95 What I claim is—

A drier comprising two concentric perforated cylinders arranged one within the other, opposite end heads therefor, hollow trunnions projecting from said heads, one of 100

said trunnions arranged to be connected with a supply of air under pressure, and the other of said trunnions closed to the exterior and provided interiorly with a deflector, and 5 a central tube opening at both ends into the said trunnions, the outer diameter of said tube being smaller than the inner diameter

of said trunnions, whereby a passage is left between the trunnions and the tube for air-currents, substantially as set forth.

DOUGLAS GORDON.
